UNITED STATES PATENT OFFICE.

JOHN HAYES, OF MUNISING, MICHIGAN, ASSIGNOR OF ONE-FOURTH TO GEORGE WILSON AND ONE-FOURTH TO FRANK HAUSLER, BOTH OF MUNISING, MICHIGAN.

WRECK-LOCATOR AND LIFE-PRESERVER.

1,199,891.

Specification of Letters Patent.

Patented Oct. 3, 1916.

Application filed September 28, 1915. Serial No. 53,024.

To all whom it may concern:

Be it known that I, JOHN HAYES, a citizen of the United States, residing at Munising, in the county of Alger and State of Michigan, have invented a new and useful Wreck-Locator and Life-Preserver, of which the following is a specification.

This invention has reference to a wreck locator and life preserver for vessels, and its object is to provide a device of the above character which will save the passengers and crew of a sinking vessel, indicate the location of the wrecked vessel, and also indicate and make a record of the month, the day of the month, and the exact time of day when the wreck occurred.

The invention comprises essentially a plurality of floats adapted to be carried by the vessel and attached thereto by suitable cables, means for equalizing the length and pull on the cables and a float controlled time indicator.

In the drawings: Figure 1 is a side elevation of a vessel embodying my invention; Fig. 2 is a perspective view of the invention showing the position it assumes after the wreck of a vessel and indicating the point where the wreck is situated; Fig. 3 is a central sectional view of the invention

the supporting frame; Fig. 4 is a front elevation of the time indicator; Fig. 5 is a perspective view of the swivel and equalizing device for the bridles.

Referring to the drawings there is shown a vessel 1, provided with a supporting frame 2, at each end, adapted to be fastened to the deck 3 of the vessel, or formed integrally therewith. Each frame is provided with compartments 4, 5 and 6. The middle compartment 5 is provided with a reel 7 having a cable or rope 8 wound thereon which is adapted to pass between, engage and travel over idle guide rollers 9, to pass upwardly through a central opening in the top of the compartment. The compartment 4 is provided with a door 10 to allow access thereto for the purpose of storing articles therein.

Two floats or life rafts 11, exactly similar in design and construction, are provided and preferably filled with compressed air, each having compressed air chambers 12 a storage chamber 13 for clothing or other articles, and a trap door 13a. Each of these life rafts is relatively flat and is of a width

and length conforming substantially to the 55 horizontal dimensions of the frame 2. As will be observed from Fig. 2 of the drawings, the compartments 2 are of substantial width, admitting of but relatively narrow passage ways on the deck at the opposite 60 sides thereof. Thus, the life rafts are of substantial size and are thereby capable of carrying a large number of persons, and are accessible from the different sides of their respective frames 2. The top of the frame 2 has an upstanding marginal flange, which is relatively short, as shown to advantage in Fig. 3. At the base of this flange, and at the inner side thereof, is arranged a marginal supporting ledge providing a supporting face spaced upwardly from the top of the frame 2, and which is adapted to receive thereon the marginal edge of the bottom of the raft. The raft is thus spaced upwardly from the frame 2, and provides 70 therebetween a relatively low space for a purpose which will hereinafter appear. A railing 14 surrounds each float 11 for the purpose of preventing persons from being washed off when the float is used as a life 80 raft. A number of life preservers or life buoys 15 are fastened to the floats in any suitable manner, which can be furnished to any persons who may need them.

In order that a record may be kept when 85 a wreck occurs, an indicator 16 is provided which is operated by clock-work, and is fastened to each float, and is provided with a float 17, which is mounted and slides in guides 18 and moves the rod 19 upward until it engages and stops the clock mechanism, as shown in Fig. 4, when the float or life 90 raft rises to the surface of the water. Each float or life raft is provided with two bridles 20 attached to the corners thereof, 95 and the cable or hawser 8 is connected or attached to said bridles by means of a swivel coupling 21 having rings 22 and 23. The swivel is for the purpose of allowing the bridles to turn with the float without becoming twisted. The bridles being loosely passed through the ring 22 and adapted to move freely therethrough automatically 100 equalize or regulate themselves to the various positions assumed by the float and are kept taut at all times. Under normal conditions of use, the floats or life rafts are seated upon the supporting frames, being 105

retained from displacement by the flange or rim provided around the edges of the said frames, as shown in Fig. 3.

When the rafts are seated within the marginal flanges of the frames 2 and upon the supporting ledges, the bridles 20, which are secured across the bottoms of the rafts, lie flat and loosely in the relatively low spaces between the frames and the rafts, and in position to be elevated and to loop downwardly without the necessity of unrolling the bridles or in any manner adjusting the same. Thus, by the provision of these low spaces the bridles are always held in position ready for use, and are prevented from becoming entangled. It will also be noted that each connecting ring 22 connects the bridles at a point beneath the central portion of the bottom of the float, and immediately over the central opening in the reel compartment 4. The swivel, likewise, is located at the central opening of the compartment, and in position to be lifted to draw the cable upwardly through the opening in the top of the frame. Each apparatus is thus always in position for immediate use, and the parts are so assembled that the bridles, the cable and the swivel connection, which prevents the twisting of the cable when the raft is turned, are in their proper relative positions and merely rise upwardly when the float or raft is raised.

The operation and utilities of the apparatus is so obvious that it is not thought necessary to make any further explanation.

I do not wish to be understood as limiting myself to the details of construction and arrangement as herein described and illustrated, as it is manifest that variations and modifications may be made in the features of construction and arrangement, in the adaptation of the device to various conditions of use, without departing from the

spirit and scope of my invention. I therefore reserve the right to all such variations and modifications as properly fall within the scope of my invention and the terms of the following claim.

What is claimed is:

The combination with a vessel, of a frame mounted on the vessel and having an intermediate compartment, a central opening in the top of the compartment, a relatively short marginal upstanding flange, and a supporting ledge within and at the base of said flange providing a supporting surface above the top of the frame, a reel mounted in said intermediate compartment, a cable wound upon the reel and extending upwardly through the central opening in the compartment, a life raft mounted on the frame and being substantially of the horizontal dimensions thereof, said raft seating at its marginal edge upon the supporting ledge whereby to provide a low space between the frame and the raft, the raft being seated within the flange to prevent edgewise displacement of the raft, bridles secured across the bottom of the raft and adapted to lie loosely in said low space in spread position ready for use, a ring connecting the bridles at a point centrally beneath the bottom of the raft and over said central opening in the reel compartment, and a swivel between the ring and the upper end of the cable adapted to lie in said low space ready to be raised by the bridles and admit the turning of the raft and the bridles without twisting the cable.

In testimony, that I claim the foregoing as my own, I have hereto affixed my signature in the presence of two witnesses.

JOHN HAYES.
